CLAIM

The ornamental design for a display screen or portion thereof with an icon, as shown and described.

DESCRIPTION

FIGURE is a front view of a display screen or portion thereof with an icon showing our new design.

The ornamental design which is claimed is shown in solid lines in the drawings. The portions of the design shown in broken lines, dotted lines or dashed lines indicate a display screen or portion thereof; the broken lines, dotted lines or dashed lines are included for the purpose of illustrating environment of the article of manufacture and form no part of the claimed design.
